UNITED STATES PATENT OFFICE.

WILLIAM HENRY SCHOONMAKER, OF MONTCLAIR, NEW JERSEY.

VALVE MECHANISM FOR INTERNAL-COMBUSTION ENGINES.

No. 809,400.

Specification of Letters Patent.

Patented Jan. 9, 1906

Application filed February 11, 1904. Serial No. 193,032.

To all whom it may concern:

Be it known that I, WILLIAM HENRY SCHOONMAKER, a citizen of the United States, and a resident of Montclair, in the county of 5 Essex and State of New Jersey, have invented new and useful Improvements in Valve Mechanism for Internal-Combustion Engines, of which the following is a full, clear, and exact description.

This invention relates to a valve especially intended as an inlet-valve for two-cycle internal-combustion engines, but useful in other connections, as will be apparent to skilled mechanics.

The leading feature of the invention as applied to internal-combustion engines resides in a casing communicating with the engine-cylinder and with the fuel-supply and having two valves respectively commanding said 20 communications and simultaneously operated by a member extending into the casing and connected suitably with the valves. The device is intended particularly to be used in connection with a reservoir in which air or a 25 mixture of air and fuel is kept stored under sufficient pressure to give it the necessary mobility through the cylinder and the passages leading thereto, and by the provision of the two valves, as explained, the movement 30 of the fluids may be controlled fully in every respect and the possibility of back explosions and other disadvantageous results prevented.

Various other features of major or minor importance are involved, and all will be fully 35 set forth hereinafter.

This specification is an exact description of two examples of my invention, while the claims define the actual scope thereof.

Reference is to be had to the accompanying drawings, forming a part of this specification, in which similar characters of reference indicate corresponding parts in all the views.

Figure 1 is a sectional plan view of the invention. Fig. 2 is a sectional elevation on 45 the line 2 2 of Fig. 1. Fig. 3 is a plan view showing a modification in the manner of operating the valves. Fig. 4 is a side elevation of the same, partly in section, on the line 4 4 of Fig. 3; and Fig. 5 is a view showing the attachment in use.

a indicates the valve-casing, which may be of any form desired, the drawings illustrating but a possible example of its construction, and as there shown said casing is provided 55 with a cap *a'*, removably fastened in place and adapted to be packed by a suitable gas-

ket, so as hermetically to seal the connection between the parts *a* and *a'*. This cap facilitates the assemblage of the various parts of the device.

Carried by or formed integral with the casing *a* are nipples *a²* and *a³*, adapted, respectively, to communicate with the engine-cylinder and with the source of combustible mixture. These nipples are interchangeable, 60 so that either may be engaged with the cylinder or with the source of mixture, as desired. The drawings show the nipple *a²* engaged with the cylinder and the nipple *a³* in position to engage with the source of fuel-supply. This engagement with the cylinder may be effected by any desired means. The nipples *a²* and *a³* are respectively commanded by puppet-valves *b* and *c*, which are seated on the extremities of the nipples, and both open 65 outward from the casing *a*. According to the arrangement illustrated in the drawings the valve *b* opens into the cylinder and the valve *c* into the communication with the source of combustible mixture. By seating the valves 70 on the extremities of the nipples *a²* and *a³* the cylinder-valve *b* opens into the body of the cylinder, and in practice I purpose locating said valve in the longitudinal center 75 of the cylinder, so that the current of inrushing mixture will be spread outward by the centrally-located valve *b* and advanced through the cylinder with an essentially uniform profile, thus effectively clearing out the 80 products of combustion within the cylinder and also assisting in the work of cooling the cylinder-walls, thus enabling the engine to be 85 operated under the two-cycle principle with a better scavenging of the cylinder and more effective cooling thereof than in the ordinary 90 type of two-cycle engine.

The valves *b* and *c* are fitted with stems *b'* and *c'*, which project, respectively, into the casing *a* and slide in suitably-arranged stem-guides *d*, carried by or formed in the casing 95 *a*. Each stem is fitted with a pin or other form of stop *e*, which limits the opening movements of the valves by striking the adjacent stem-guides *d*. The valves *b* and *c* are operated to open and close simultaneously, and preferably this is done by means 100 of devices passing from the cam-shaft or other actuating means into the casing *a*. As here shown, said devices comprise a rocking shaft *f*, passing vertically through a stuffing-box *g* in the bottom of the case *a* and having 105 its upper end fitted in a suitable bearing *a⁴*,

formed on or carried by the cap *h'*. The said shaft or rod *f* has two arms *a* and *i* attached thereto, preferably through the medium of a sleeve *k*, and said arms respectively engage 5 in the recesses formed in the stems *b'* and *c'*, so that by the rocking of the shaft *f* in one direction the valves *b* and *c* are opened and by the rocking of the shaft in the opposite direction the valves are seated.

10 In the operation of the device after the proper connections are made when the cylinder is to be charged the shaft *f* should be rocked in the direction of the arrow shown in the drawings, thus simultaneously opening 15 the valves. The combustible mixture will then flow through the nipple *a³*, case *a*, and nipple *a²* and into the cylinder, the valve *b* acting meanwhile to spread out the inrushing gases and cause them thoroughly to scavenge 20 the cylinder and force out before them the products of previous combustion therein. As the piston begins its return movement the valve *b* will be seated by the compression in the cylinder, the valve *c* also being 25 actuated in this direction by the pressure in the source of fuel and air supply. It will therefore be seen that the valves need to be mechanically driven only in one direction; but for the purpose of securing a positive 30 action I prefer to drive the shaft *f* positively in both directions, thus bringing about a positive seating and unseating of the valve. The new arrangement which I have provided enables me not only to thoroughly cleanse the 35 cylinder by the inrushing charge, but also provides a secure seal for the air and gas which may be stored under pressure and prevents this pressure from exerting itself to tend to open the valve *b*. It also seals both 40 the connection to the cylinder and to the fuel-supply and prevents thereby the possibility of a back explosion.

The modification shown in Figs. 3 and 4 provides for operating the valves in the same 45 manner as before explained and also for allowing the valves a rotating movement in their seats. This effect I attain by forming on the valve-stems *l* annular rack-teeth *l'*, adapted to mesh with a double-faced pinion 50 *m*, mounted on the shaft *f* in place of the arms *h* and *i*, before described. It will be observed that by rocking this shaft the necessary movement will be imparted to the valve-stems, and at the same time said stems 55 with their attached valves will be allowed a free turning movement in the valve-seats, thus enabling them to seat effectively and clear out by their natural grinding action any

obstructing accumulations which might form on the seats. 60

Various changes in the form, proportions, and minor details of my invention may be resorted to at will without departing from the spirit and scope thereof. Hence I consider myself entitled to all such variations as may 65 lie within the intent of my claims.

Having thus described my invention, I claim as new and desire to secure by Letters Patent—

1. The combination of a valve-stem mounted to reciprocate and to turn and having annular or part-annular rack-teeth thereon, and a pinion meshed with the rack-teeth, to impart reciprocal movement thereto. 70

2. The combination of a casing comprising two communications, valves commanding said communications, crossing valve-stems located in the casing and having annular rack-teeth formed thereon, a rock-shaft extending into the casing, and a pinion or pinions attached to the shaft and meshed with the rack-teeth of the valve-stems. 75

3. The combination of two crossing valve-stems having annular rack-teeth thereon, and a toothed gear meshed with the said rack-teeth to operate the valve-stems. 80

4. The combination of a casing having inlet and outlet communications, valves respectively commanding the said communications, crossing stems connected with the valves, a rock-shaft extending into the casing, and means within the casing for simultaneously and positively operating the valves and stems from the rock-shaft. 85

5. The combination of a casing having inlet and outlet communications, outwardly-opening valves commanding the same, a rock-shaft extending into the casing, and means within the casing for simultaneously and positively operating the valves from said rock-shaft. 90

6. The combination of a casing having inlet and outlet nipples, outwardly-opening valves seated on the outer end of said nipples, valve-stems connected respectively to the valves and extending into the casing, and a means projecting into the casing and connected with the stems to simultaneously and positively operate the valves. 105

In testimony whereof I have signed my name to this specification in the presence of two subscribing witnesses.

WILLIAM HENRY SCHOONMAKER.
